UNITED STATES PATENT OFFICE

JAMES M. PAYNE, JR., OF DUNBAR, WEST VIRGINIA, ASSIGNOR TO F. W. WOOLWORTH COMPANY, A CORPORATION OF NEW YORK

DESIGN FOR A TUMBLER

Application filed October 29, 1930. Serial No. 37,430. Term of patent 7 years.

To all whom it may concern:

Be it known that I, JAMES M. PAYNE, Jr., a citizen of the United States, residing in Dunbar, in the county of Kanawha, and State of West Virginia, have invented a new, original, and ornamental Design for a Tumbler, of which the following is a specification, reference being had to the accompanying drawing, forming part thereof.

The figure is a view in side elevation of a tumbler showing my new design. The tumbler is of conventional circular contour in cross section.

I claim:

The ornamental design for a tumbler, as shown and described.

JAMES M. PAYNE, JR.
